Inventor;

Thomas Payne.

UNITED STATES PATENT OFFICE.

THOMAS PAYNE, OF RIDGEFIELD, CONNECTICUT.

CLOTHES-SPRINKLER.

Specification of Letters Patent No. 22,669, dated January 18, 1859.

To all whom it may concern:

Be it known that I, THOMAS PAYNE, of Ridgefield, in the county of Fairfield and State of Connecticut, have invented certain new and useful Improvements in the Manufacture of Clothes-Sprinklers; and I do hereby declare that the following is a full, clear, and exact description of the same, reference being had to the accompanying drawings, in which—

Figure 1, represents a perspective view of said clothes sprinkler. Fig. 2, represents a longitudinal vertical section, through the same.

15 The nature of my invention relates to the particular construction of a clothes sprinkler, whereby the article is more easily handled, and less liable to get out of order, and possesses greater conveniences than any thing 20 heretofore devised for a similar purpose.

To enable others skilled in the art to make and use my invention, I will proceed to describe its construction and operation.

25 A, represents the cylindrical body of the clothes sprinkler to which is soldered the handle B.

C, represents the top of the clothes sprinkler, which is perforated by the holes a, in the usual manner.

30 b, represents the conical rim of the orifice D.

d, represents a stopper of metal, or any other suitable material, which fits exactly within the conical orifice, and which is 35 formed with a flange f, which is made to fit exactly against the inner side of the top C, so that when the stopper d, is pressed within the orifice D, it shall close said orifice.

E, represents a spiral spring which at one 40 end is secured to the bottom of the stopper d, and which rests with its other end on the

bottom G, of the clothes sprinkler; the spring E, is steadied in its play by means of the cylinder h, in which it is confined. Thus it will be seen that the action of the spring E, 45 presses the stopper d, constantly against the orifice D, and keeps it thus closed.

To fill the clothes sprinkler with water, the nozzle of the pitcher may be made to rest upon the stopper d, as represented in Fig. 2, 50 the stopper is pressed down by the weight of the pitcher, the orifice D, is opened, and the water can be poured in. On removing the pitcher, the orifice D, is closed by the action of the spring E.

In clothes sprinklers heretofore used, the orifice has been closed by means of a cork or a screw; but as the implement when so made, is inverted when used for sprinkling, and as the water therein is actuated with 60 considerable power, it causes the cork to fly out; in using a screw stopper, the threads of the screw soon wore out by frequent application; these difficulties are entirely obviated by the above described construction 65 of my clothes sprinkler. Besides where the stopper was separate from the article itself, it was likely to be lost or mislaid. None of these objections arise in the sprinkler, as I construct it.

Having thus fully described the nature of my invention what I claim therein as new and desire to secure by Letters Patent is—

A clothes sprinkler having an interior self closing stopper, and made and operating, 75 substantially in the manner and for the purpose herein set forth.

THOMAS PAYNE.
